JOSEPH R. B. NORFOLK, OF CHICAGO, ILLINOIS, ASSIGNOR TO NATURAL MOVEMENT ARM AND APPLIANCE COMPANY, OF CHICAGO, ILLINOIS, A CORPORATION OF ILLINOIS.

ARTIFICIAL LIMB.

1,293,885.

Specification of Letters Patent. Patented Feb. 11, 1919.

Application filed November 26, 1917. Serial No. 203,881.

To all whom it may concern:

Be it known that I, JOSEPH R. B. NORFOLK, a citizen of the United States, and a resident of Chicago, in the county of Cook and State of Illinois, have invented certain new and useful Improvements in Artificial Limbs, of which the following is a specification:

My invention relates to artificial limbs, and in the present adaptation thereof, to artificial arms and hands. Its principal and fundamental object is to provide an artificial member which may be of suitable weight and shape, having simple and effective operative mechanism, and adapted to take the place of the amputated member of the wearer and provide for the wearer a conveniently attachable artificial structure having notable advantages in service. Specific objects arising from structural details and arrangement of parts are, to provide an upper arm, forearm, wrist, and hand combination in which the movement of the upper arm stump will simultaneously flex the artificial elbow joint and turn the wrist joint in substantially natural movements, and by positively-acting and simple means; to provide in such a structure means for positively maintaining the forearm and its connected parts in extended position, for instance in an upwardly and outwardly raised position, so long as the stump of the upper arm is maintained in such position; to provide in such a structure automatic locking means adapted to maintain the forearm in a given angular relation to the upper arm, as for carrying a coat upon the forearm, with provisions for releasing the forearm from such locked position by an easy and natural movement of the upper arm through the movement of the stump; to provide in such a structure, including a hand having flexible fingers and thumb, means for contracting the fingers and thumb, and also the forefinger and thumb independently, through the action of the shoulder opposite to the one carrying the artificial member, and this by simple, positively acting and comfortably operated means; to provide an improved character of articulating joint for the phalanges; to provide improved means associated directly with the fingers for bend-

ing them at the joints; to provide means for automatically locking the fingers in one or more given position of contraction; to provide means whereby irregular objects, or objects larger at one end than at the other, may be grasped by the artificial hand with the fingers thereof substantially equally engaging the object; to provide a form of connection between the artificial arm and the wearer's body which will permit the weight of the artificial member to be carried conveniently and comfortably by the shoulder and afford a considerable variety of movements approximating the natural movements of the human arm; and to provide an artificial member not likely to get out of order, but which is susceptible of repair and replacement of parts with a marked degree of convenience considering the nature of devices of this kind. Other objects and advantages will appear hereinafter.

A preferred embodiment of the invention is shown in the accompanying drawings, which form a part of this specification. In these drawings Figure 1 is a front view of the device as it would appear on the wearer's body;

Fig. 2 is an enlarged side view of the upper arm and shoulder device to which it is attached;

Fig. 3 is a face view of the hand, and a medial section of the wrist, forearm and part of the upper arm;

Fig. 4 is a side view of the parts of Fig. 3, the forearm and wrist being in medial section;

Fig. 5 is an enlarged section on the line 5—5 of Fig. 4;

Fig. 6 is a plan view of the wrist and hand with the upper part cut away to show the operating mechanism, the fingers being in section on various planes in order to show the joint construction and the flexing links;

Fig. 7 is a longitudinal section through the hand, as on the line 7—7 of Fig. 6; and

Fig. 8 is a section on the line 8—8 of Fig. 6, the sectional views being in the directions of the arrows.

The general exterior construction and means for securing the arm to the body is shown in Fig. 1, the attaching and finger-operating straps being shown in the posi-

tion they assume when on the body of the wearer.

In its general parts the limb comprises an upper arm 10, a forearm 11 pivotally connected thereto, a wrist portion 12 adapted to rock relatively to the forearm, a hand 13 movably attached to the wrist, articulated fingers 14, and a thumb 15.

For the adaptation of the invention illustrated the wearer is to be understood as having a stump or arm portion comprising a part of his natural upper arm. The stump is thrust into the part 10, which is hollowed to fit the stump, as is well understood in the art. The artificial arm is held in this position by means of a shoulder pad 16 secured by an adjustable strap 17 passing under the arm pit and by an adjustable strap 18 passing around the body and under the opposite arm.

In the connection between the artificial arm and the shoulder pad provision is made for moving the upper part of the arm 10 in two main directions, first, in a plane substantially parallel to the side of the body, and second, in a plane substantially perpendicular to the side of the body. For this purpose a plate or support 19 is pivotally mounted at each of its ends to brackets 20 secured to the shoulder pad 16. To this plate 19 is pivotally connected, as at 21^a, a supporting bar 21 rigidly secured to the upper arm 10, as by screws or rivets. The upper arm 10 may therefore move to the front or back by its swinging on the pivot 21^a and may move outward from the side through the rocking of the support 19 on its pivots. These movements and various combination movements are produced by moving the stump in the various desired directions, the part 10 of the artificial arm acting as a continuation of the stump and partaking of its movements. The combination movements mentioned are such as include some forward or backward motion with some outward motion, and the construction shown provides for substantially all of the movements possible to the stump of the upper arm. The upper arm may thus be swung about in any natural arc or circle and may be raised with a forward, rearward or directly outward movement so as to extend in all or substantially all of the natural directions.

The forearm 11 is pivotally connected to the upper arm 10 by a short bolt 22 located near the front of the arm so as to allow the forearm unimpeded movement in a forward direction. Rearward movement of the forearm relatively to the upper arm is prevented by the engagement of the rear edge 23 of the forearm with the rounded end of the upper arm therat.

The forearm is automatically moved rela-

tively to the upper part of the arm by means of a link 24 pivotally connected at its upper end to the shoulder plate or main support 19, as at 25, and at its lower end to the forearm at a point 26 spaced from the pivot 22 to provide leverage. The pivot 25 is arranged rearward of the point of connection 21^a between the upper arm 10 and the plate or support 19, while the pivot 26 is in front of the pivot 22, so that if the upper arm 10 be moved forward the forearm simultaneously moves forward and its free end is drawn upward, as shown by dotted lines in Fig. 2. The link 24 being a rigid piece in itself, preferably of steel, the movement of the forearm is always positive, and the forearm is maintained positively in the various positions it may assume through the movements of the upper arm, including positions in which the arm is directed upward.

A feature of advantage is in the provision of a lock or latch 27 pivotally mounted on the upper arm 10, as at 28. A notch 29 at the free end portion of this latch is adapted to engage a projection 30 on a plate 31 mounted on the inner wall of the forearm. The latch is held in position to engage this projection by a compression spring 32 adapted to bear against the upper end 27^a of the latch. When it is desired to engage the latch with the projection 30 the upper arm 10 is moved forward until the forearm comes substantially into a horizontal position, as shown in Fig. 2, whereupon the locking engagement takes place and the arm structure may then be moved into a large variety of positions, while still maintaining the locked relation of the upper arm and forearm, so long as the upper arm is not moved forward so as further to raise the forearm. When it is desired to release the forearm from its locked position a simple forward movement of the upper arm brings the projection 31 into the indented portion 33 of the latch and upon any further movement in either direction the latch engages the side instead of the top of the projection 30 and is sprung aside so long as the catch and latch are in relative movement and contact with each other.

In order that the movements of the artificial limb may further simulate the movements of the human limb the wrist is formed to rotate simultaneously with movements of the arm so as to turn the palm of the hand inward in the forward and upward movement and the reverse in the backward and downward movement of the forearm.

The wrist comprises a tubular portion 34 adapted to rotate in the lower portion of the forearm, as shown more particularly in Figs. 3 and 4. Rotation of the wrist is brought about by the bevel pinions 35 and

36, the former being connected to the wrist portion 34 by a shaft 37 and yoke 37^a, while the pinion 36 is connected by links 42 and 43 to the upper arm. These pinions 35 and 36 are mounted on a bracket 38 secured to the inner wall of the forearm. The pinion 36 is mounted on a shaft 39, to which it is connected by a locking or motion-communicating screw 40 which enters an arcuate slot or recess 41 in the shaft 39, which arrangement allows a certain amount of play between the pinion and the shaft. The purpose of this provision of lost motion is to restrict the movement of the wrist to that which is provided by the latter part of the upward movement of the forearm. If desired, however, the pinion 36 may be locked to the shaft 39 by bringing the end of the set-screw into engagement with the bottom of the recess 41. The link 42 is rigidly mounted on the shaft 39 and is connected pivotally at 44 to the link 43, which link 43 is pivotally attached to the upper arm 10 at 28. As the pin 28 is arranged in front of the pivot bolt 22, about which the forearm turns, upward movements of the forearm give the links 42 and 43 a toggle movement at the joint 44 causing the link 42 to move in the direction of the arrow in Fig. 3 and turning the shaft 39.

For retaining the wrist in place in its socket, screws or pins 44, which extend through slots 45 in the lower part of the forearm, are provided, one of the slots being shown in Fig. 1.

The hand is pivotally connected to the wrist by a pin 46 whereby the hand has some hinge-like movement at this joint.

Each finger 15 comprises three segments or phalanges 47, 48 and 49 pivotally connected together and to the hand 13. Similarly the thumb consists of a segment 50 pivoted to the hand and an end portion 51 pivoted to the segment 50. Screws 52 are used to unite the various contiguous phalanges of thumb and fingers respectively to each other.

Provision is made for simultaneously moving the fingers and thumb and also for moving the thumb and forefinger simultaneously independently of the movement of the other fingers to grip objects therebetween.

The fingers are moved by means of pivotally hinged or jointed rods 53 in series secured by pins 94 to the tips, or outermost phalanges of the fingers and passing along freely and slidingly within the fingers adjacent to their inner surfaces respectively, as shown more particularly in Fig. 7. Since these links 53 pass on the inner side of the segments and their pivotal points of connection 52 a pull on the links causes the fingers to contract, and, conversely a push on the rods causes the fingers to open. Backward

movement of the fingers is limited by means of shoulders 54 which engage projecting portions 55 on the adjacent segment. A wrapping of rawhide is finally placed around the fingers and thumb respectively, as may be considered illustrated in Fig. 1, to give them finish and to strengthen the wood of the phalanges to resist the strains of the rods 53 and 70.

At their inner ends the links 53 which operate the fingers are pivotally connected to a cross-bar 56 by means of screws 57 or the like. This bar 56 is bodily movable toward and from the fingers and is in the nature of a whiffletree equalizer and enables the fingers to adjust themselves to the shape of the article gripped. For instance, if the article is thickest adjacent to the forefinger the forefinger will close sufficiently to grasp it while the little finger will also close upon the object by moving to a greater extent. The other fingers will assume intermediate positions between the two extremes.

This equalizer is preferably made of U-shaped cross-section so as to inclose the ends of the rods 53. Adjacent to its center it is cut away to receive the end of a pull rod 58 pivotally connected to it by a screw 59. A pull upon this rod 58 closes the fingers. The equalizer tilts on the rod 58 according to the shape of the object grasped while the rod 58 maintains it always in operative position.

The pull rod 58 slides in guides 60 attached to a plate 61 secured at 62 (Fig. 7) to the inner palm portion of the hand. Three springs 63 are connected at one end respectively to a bracket 64 carried by the rod 58 and at the other end to the body of the hand 13 in spaced apart relation. The rod 56 is normally held by these springs in the position shown in Fig. 6, in which position the fingers are held extended. The pull movement of the rod closes the fingers against the tension of these springs.

I have found it desirable at times to be able releasably to hold the fingers in a given retracted position, and have provided a locking device which will so hold the fingers at will. This device comprises a pawl 65 pivotally mounted on the rod 58 at 66, and a series of rearwardly extending projections 67 formed on a bracket 68 attached to the plate 61. A flat spring 69 mounted on the forward end of the plate 61 bears against the projections 67 and insures the engagement of the pawl 65 with the projections 67 as the free end of the pawl passes between the spring 69 and the projections 67. Thus the locking engagement is bound to take place when the rod 58 is released and the head of the pawl is close to the holding side of one of the projections 67. Disengagement is brought about by pulling on the rod 58, whereupon the spring 69 causes the head

of the pawl to pass between the projections 67 or, in other words, through one of the openings 67^a or around the end at 67^b (according to the projection engaged) and on releasing the rod 58 from pulling strain the pawl head rides back into its original position as shown in Fig. 7 over the back of the part carrying the projections 67. A light spring 95 holds the pawl against displacement.

The jointed rod 70 which operates the thumb is not connected to the equalizer 56 which operates the fingers, but its inner end is connected to the bar 58 by a cord 71, a link 72, and a bracket 73. A cord 74 which pulls in opposition to a spring 75 is provided for closing the thumb. To this cord 74 is attached a second cord 76 connected to the equalizer bar 56 adjacent to the point of connection of the latter to the series of links for operating the forefinger. With this arrangement a pull on the cord 74 produces not only a retraction of the thumb but also of the forefinger as well, enabling articles to be gripped between the thumb and forefinger. This action of the thumb and forefinger is independent of any substantial movement of the other fingers.

The cords 65 and 74 pass through the forearm over pulleys at 90 into tubes 77 and 78 in the upper arm. The cord 65 passes over the wearer's back and is connected to a shoulder pad 79 in the form of a loop adapted to encircle the shoulder and bear against the front thereof, while the cord 74 passes over the wearer's chest and is attached to a similar shoulder pad 80 adapted to bear against the rear part of the same shoulder. When a pull is exerted upon the cord 65 the fingers are partially closed before the thumb is moved in a closing direction. This action is derived through the cord 71 and link 72, Fig. 6, the latter engaging the stop 80 on the plate 73 and communicating a pull upon the cord 71 and consequently to the link end 70 controlling the thumb movement. Thus the thumb closes in upon the fingers or object held thereby in a very natural way.

From this description it will be evident that forward movement of the opposite shoulder, or the one not carrying the artificial member, will produce a pull on the cord 65, and that similarly a backward movement of the shoulder will draw up on the cord 74. Consequently if the opposite shoulder be moved forward the fingers will be closed and the thumb will also be moved inward, while if the opposite shoulder be moved backward the thumb and forefinger only will be closed. It should be noted that the opposite shoulder is free to move in a circular direction and that substantially all uses may be made of the opposite arm with-

out any pulling effect upon the cords which 65 will operate the artificial fingers.

A feature of improvement is in the specific form of joint between the phalanges. In Fig. 7 the construction is shown in side view, and in the second finger of Fig. 6 it is 70 shown in top view. It includes a projecting member 85, ordinarily about an eighth of an inch wide, adapted to interfit with a recess in the adjoining phalange or section. Ordinarily the finger sections are made of wood 75 or similar light-weight and fibrous material which would not successfully take many of the strains which the fingers are called upon to bear, especially as to the relatively narrow projecting tongue-like part if also made of 80 wood. The projecting part 85 is therefore made of metal. It is substantially circular in side view and is provided with an integral stud 86 and a metallic leaf 87, the latter being secured as by welding to the part 85, 85 the leaf 87 terminating in the projection 55 acting as a stop for the adjoining phalange, as hereinabove mentioned. A screw 88 passes through the leaf 87 and through a hole in the stud 86, and another screw 89 90 further secures the leaf 87 to the wood section. Thus the projecting tongue 85 is quite rigidly secured to the phalange and is capable of withstanding severe strains. The adjoining phalange interfits, as illustrated, and 95 the screw 52, which is preferably threaded only in the center so as to thread into the part 85, holds the two adjoining sections together with a hinge joint of satisfactory strength and operation.

It is pointed out that quite heavy loads may conveniently be carried by the artificial arm inasmuch as the weight is carried directly by the shoulder pad 16, and, through the locking of the fingers in more or less 105 closed relation as desired an article, such as a suit case, for instance, may be grasped by the artificial arm and conveniently carried without further effort than to secure the desired locked finger condition, which is accomplished through a simple movement of the opposite shoulder.

The cords 65 and 74 are preferably in the form of flexible steel cables. They are rendered adjustable as to their length in relation 115 to the shoulder pads 79 and 80 by clasps at 92 and 93 respectively whereby the exact tension of these cords for operating the finger may be obtained initially and from time to time as may be desired. These cords provide a direct pull upon the mechanism in the hand operating the fingers, a feature advantageous in action as well as in simplifying the construction.

The illustrations show what I consider to 125 be a preferred and highly advantageous form of the structure, but the invention is not limited strictly to the construction and

arrangement of parts specifically shown, as modifications of various of these parts may be made without departing from the principle of operation or the spirit of the invention disclosed.

5 I claim:

1. In combination, an artificial hand body, a plurality of fingers comprising hingedly jointed sections extending from said body, a 10 push and pull rod comprising links hinged together secured to the outermost joint section of each finger, and extending freely slidingly on the inner side of the joint connections of each thereof, a whiffle-tree-like 15 equalizer within said body and connected to each of said series of links at spaced apart portions of the equalizer, said equalizer extending transversely of the ends of said rods and being mounted to move bodily toward 20 and away from the fingers, and means for moving said equalizer in a direction away from the fingers to contract the fingers.

2. In an artificial hand, the combination 25 of a hand body and a series of jointed fingers extending therefrom, a jointed push and pull member slidingly mounted to move freely in each finger on the inner side of the finger joints, a transversely arranged equalizer in the hand body mounted to 30 move bodily throughout all portions thereof toward and away from said fingers, each of said push and pull members being secured in spaced apart relation to said equalizer, and a device connected to said equalizer effectually midway of its ends for pulling 35 upon said equalizer to move all portions of the same substantially equally.

3. In an artificial hand having jointed 40 fingers and pull members in each for flexing the fingers, the combination therewith of an equalizer mounted whereby all portions thereof may move substantially equally toward and away from the fingers, a connection between said pull members respectively 45 and said equalizer at spaced apart portions of the equalizer, said equalizer extending transversely of the inner ends of the fingers, and a bar extending substantially at right angles to said equalizer and pivotally connected substantially midway of the ends of 50 said equalizer for pulling upon the same, said bar being slidably mounted, said equalizer being mounted to tilt on said bar whereby said fingers may close in upon a 55 tapering object with the fingers on one side of the hand closing in farther than those on the other side of the hand.

4. An artificial limb comprising an upper 60 arm, a forearm jointed thereto, and a hand, an anchoring member adapted to be secured to the body of the wearer adjacent to the shoulder, a link capable of transmitting push and pull strains pivotally connecting said forearm and said anchoring

member, the point of connection of said link 65 with the forearm being offset with respect to the pivotal connection between the upper arm and the forearm whereby moving the upper arm also moves the forearm upon its joint connection.

5. A hand device of the type set forth comprising in combination a hand body, a series of flexible fingers jointed to said body, including pull members in the fingers respectively, an equalizer in the hand body of the whiffle-tree type having freely movable ends secured to the pull members for closing the fingers simultaneously, said equalizer being mounted for free bodily movement toward and away from said fingers, and a pulling bar slidably mounted in the hand body and pivotally connected to the equalizer substantially medially of the ends thereof for moving both ends of the same with a substantially equal movement, 80 said equalizer being also mounted to tilt on said pivotal connection whereby one end thereof may move farther than the other end thereof, the arrangement being such that the closing of the fingers on one side of the 90 hand will be increased and on the other side decreased according to the shape of the object being grasped.

6. An articulated artificial arm having means for securing same to one shoulder, 95 said arm carrying a hand having thereon articulated fingers and a thumb, pull members in the fingers and thumb respectively for flexing the same, a draft device within the hand body, said pull members being connected effectively to said draft device, two tension members extending from said hand to the opposite shoulder, each tension member having a loop portion for engaging the shoulder, one of said tension members being 100 connected to said draft device for closing the fingers and thumb simultaneously by one movement of said shoulder, and an auxiliary draft device in the hand body, the pull members of the thumb and forefinger being connected effectively to said auxiliary draft device, the other of said tensioning devices being connected to said auxiliary draft device for closing the forefinger and thumb 110 independently of the movement of the other fingers by another movement of said shoulder.

7. An artificial arm comprising an upper arm, means for supporting the same from one shoulder, a forearm mounted upon the upper arm, a hand body mounted on the forearm, said hand body having articulated fingers and a thumb thereon movable relatively thereto, pull members in each of the fingers and thumb, a movably mounted draft device in the hand body, the pull members of the fingers being connected to said draft device, a tension member connected to said

draft device, said tension member having a loop for surrounding the opposite shoulder for contracting the fingers simultaneously by one movement from such opposite shoulder, a second tension member also having a loop for surrounding the opposite shoulder, said second tension member being connected to the pull member of the thumb and also connected effectively to the pull member of the forefinger for contracting the thumb and forefinger simultaneously by another and different movement of such opposite shoulder.

8. In an artificial hand the combination of a hand body having flexible fingers and a flexible thumb extending therefrom, pull rods in the fingers and in the thumb for flexing the same, a pair of tension members extending from the artificial hand to the opposite shoulder and each there terminating in a shoulder loop, one of said tension members being connected effectively to the pull rods of the fingers, the other tension member being connected effectively to the pull rod of the thumb, and a connection effectively between the pull rods of the fingers as one unit and the pull rod of the thumb as another unit.

9. In artificial arm structure, the combination of a shoulder pad, means for holding same upon the wearer's shoulder, a bracket pivotally mounted on said pad, an upper arm pivotally mounted on said bracket, a lower arm jointed to said upper arm, and a substantially rigid bar-like connection pivoted to said bracket at a place offset from the pivotal mounting of said upper arm to said bracket, said connection being also pivoted to said lower arm at a place offset from its upper arm joint.

10. An artificial arm comprising an upper arm, a forearm on said upper arm, a hand portion on said forearm, articulated fingers on said hand portion and mounted to move relatively thereto, pull members in said fingers for flexing the same, a draft device movably mounted in said hand and to which the pull members are attached, a pawl associated with said draft device for holding the same in a retracted position, means extending from said unitary device and adapted to be connected to the shoulder opposite the one having the artificial arm for pulling upon said draft device.

11. In an artificial hand having flexible fingers, means for flexing the fingers comprising in combination push and pull rods in the fingers, a cross bar at the ends of said rods and connected to the same, a slidably mounted member in the hand body, a connection between said slidably mounted member and said bar, a plurality of springs connected to a relatively fixed part and to said slidably member for drawing the same toward

the fingers, and a catch device associated with said slidably member for retaining same releasably in a given position of retraction.

12. A catch device for an artificial hand comprising a movable member, a pawl pivotally mounted thereon, said pawl having a head thereon extending to one side of the body of the pawl, a holding member for the pawl head comprising a plurality of teeth in the path of said laterally extending head, there being openings between the teeth through which said head may pass, and spring means for forcing said pawl in the direction of said teeth.

13. In combination, an artificial hand body, flexible fingers and a flexible thumb mounted thereon, a push and pull rod in each of said flexible fingers and thumb for flexing the same, a cord connected to the push and pull rod of the thumb and a cord connected to the push and pull rod of the forefinger, said two cords being secured together, tensioning means extending from said two cords and terminating in a loop for the opposite shoulder, a movable member in the hand body connected to the push and pull rods in the fingers, and a tensioning member extending from said movable member and also terminating in a loop for said opposite shoulder.

14. An articulated artificial arm, means thereon for securing the same to one shoulder, a hand body on said arm and articulated members comprising phalanges in series on said hand body, pull means in the articulated members for flexing the same, a pair of tension members connected to the pull members, one thereof being adapted to extend across the back of the wearer and being operatively connected to the pull members in at least one of the articulated members, the other being adapted to extend across the front of the wearer and being connected to the pull members in at least one other of the articulated members, when the device is normally in use, each of said tension members having a loop for surrounding the shoulder opposite the one carrying said artificial arm.

15. In an artificial arm, the combination of a shoulder pad member for the stump arm, means for holding same upon the shoulder, an upper arm member pivotally mounted on said pad member, a lower arm member pivotally mounted on said upper arm member to form an elbow joint, and a rigid bar pivotally mounted on the pad member and also on the forearm member, the pivotal connections at each end of the bar being offset from the pivotal connections of the upper arm to the pad member and that of the lower arm to the upper arm member respectively, whereby a movement of the upper arm moves the lower arm at the elbow joint.

- through said bar and when the arm is raised said bar sustains the lower arm in raised position.
16. In an artificial arm, the combination 5 of a shoulder pad member for the stump arm, means for holding same upon the shoulder, a bracket normally transverse of the shoulder and mounted to rock on the pad member, and an upper arm pivotally mounted on said bracket.
17. In an artificial arm, the combination 10 of a shoulder pad member for the stump arm, means for holding same upon the shoulder, a bracket normally transverse of the shoulder and mounted to rock on the pad member, a forearm pivoted upon the upper arm, and a rigid bar pivoted on said bracket at a point spaced from the upper arm pivot thereon, said bar being pivoted also on the lower arm at a point spaced from its pivoted connection to the upper arm.
18. In an artificial arm having an upper and a lower arm member pivoted together and having a hand member mounted to rock 15 thereon on the axis of the lower arm, means for rocking said hand member when the upper arm member is moved, said rocking means comprising in combination a gear mounted in the lower arm member, a toggle 20 lever having one end pivoted to the upper arm member at a point offset from the pivotal connection between the upper and lower arm members, the other end of the toggle lever being operatively connected to said 25 gear, a second gear meshing with the first mentioned gear, and a connection between said second gear and said hand member for rocking the hand member when said second gear is rocked.
19. In an artificial hand having a hand 30 body the combination of a transversely arranged bar in the hand body, flexible fingers extending from the hand body and having pull members therein, said pull members being connected to said transverse bar, a flexible thumb also extending from said hand body, a pull member in the thumb for flexing the same, means under the control of the wearer for pulling upon said transverse 35 bar substantially midway of the ends thereof to flex all the fingers simultaneously, and other means under the control of the wearer and connected to said transverse bar adjacent to the thumb and also connected to said 40 pull member in the thumb for retracting the forefinger and thumb substantially independently of any movement of the other fingers.
20. In an artificial arm device, the combination 45 of an arm member and a hand member mounted to rock thereon, means including a pair of intermeshing gears for rocking the hand member, rocking means for one of said gears, one of said gears being 50 substantially loosely mounted to rock a pre-determined amount before rocking motion is imparted to said hand.
21. In artificial arm structure, the combination 55 of a support, means for securing said support upon the wearer's shoulder, an artificial upper arm mounted upon said support with a universal joint, an artificial lower arm hinged to said upper arm, and a substantially rigid connection pivotally mounted at one end on said support at a 60 place offset from the pivotal connection of the upper arm to the support, and pivotally mounted at its other end to said lower arm at a place offset from its hinge connection to the upper arm.
22. In an artificial arm, the combination 65 of a shoulder pad member for the stump arm, adjustable strap-like means adapted to pass across the wearer's arm pit there for holding said pad upon the shoulder, adjustable strap-like means extending from the pad member and adapted to pass around the wearer's body under the opposite arm pit also for holding the pad member upon the shoulder, and an arm member mounted upon 70 said pad member with a universal hinge joint.
23. An articulated arm comprising an upper arm and a forearm pivotally connected thereto, an anchoring member adapted to be 75 secured to the adjacent shoulder of the wearer, said upper arm being pivotally connected to said anchoring member, a push rod pivoted at one end to the anchoring member rearward of its connection to the 80 upper arm and pivoted at its other end to the forearm forward of its connection to the upper arm.
24. An artificial member comprising an 85 upper arm, a forearm, a hand body, articulated fingers and a thumb mounted thereon and movable relatively thereto, means in the forefinger and thumb for flexing the same independently of substantial movement of the other fingers, and tensioning 90 means extending from said means in the forefinger and thumb to the opposite shoulder for flexing the thumb and forefinger 95 simultaneously by a movement of the opposite shoulder.
25. The combination of a hand body, a guiding structure rigidly secured thereto, a bar slidably mounted to move vertically in said guiding structure when the hand is pointed downward, a plurality of fingers on the body, push and pull rods operatively in the fingers, a cross member carried by said bar, said push and pull rods being secured to said cross member, spring means for drawing said sliding bar and cross member 100 toward the fingers, a jointed thumb on the hand body, means in the thumb for flexing the same, and a connection between said 105

sliding member and said thumb-flexing means for communicating movement thereto.

26. In combination, an artificial hand body, a bracket secured on the inside thereof and extending longitudinally thereof, said bracket having guides for a push-and-pull member, a push-and-pull member slidably mounted in said guides, a transverse member pivotally mounted on said slidably mounted push-and-pull member, a plurality

of fingers flexibly mounted on the hand body, a push-and-pull rod in each finger for flexing the same, said push-and-pull rods being connected to said transverse member, spring means for drawing said slidably mounted push-and-pull member toward the fingers, and means under the control of the wearer for pulling upon said slidably mounted push-and-pull member.

JOSEPH R. B. NORFOLK.
